UNITED STATES PATENT OFFICE.

GEORGE WEBSTER, OF CHRISTIANA, PENNSYLVANIA, ASSIGNOR OF ONE-HALF TO ISAAC H. DICKINSON, OF QUARRYVILLE, PENNSYLVANIA.

DESIGN FOR A KNIFE-BLADE.

SPECIFICATION forming part of Design No. 27,716, dated October 12, 1897.

Application filed August 17, 1897. Serial No. 648,603. Term of patent 14 years.

To all whom it may concern:

Be it known that I, GEORGE WEBSTER, a citizen of the United States, residing at Christiana, in the county of Lancaster and State 5 of Pennsylvania, have invented and produced a new and original Design for Knives for Dehorning Implements, of which the following is a specification, reference being had to the accompanying drawings, of which—

10 Figure 1 is a plan view of a knife for dehorning implements, showing my new design. Fig. 2 is a section on line $\alpha\alpha$, Fig. 1.

As shown in the drawings, the leading or material feature of my design consists of a 15 flat segment or plate a with a beveled cutting edge b of the curvilinear shape shown—that is to say, about one half b' of the edge is substantially in the arc of a circle struck from a

given center, and the other half b^2 thereof is substantially in the arc of a larger circle 20 whose center is substantially on the same line as the line $\alpha\alpha$, Fig. 1, bisecting the plate transversely as the center of the circle of the half b' , the two portions $b' b^2$ constituting a continuous cutting edge. 25

What I claim as new, and desire to secure by Letters Patent, is—

The design for a knife for dehorning implements substantially as shown and described.

In testimony whereof I have hereunto affixed my signature in the presence of two 30 subscribing witnesses.

GEORGE WEBSTER.
